OTHER PUBLICATIONS Pictures of Unscripted Lid hats, as shown on <http://unscriptedgear.com>. Downloaded Sep. 13, 2010 (9 pages).*Primary Examiner — Karen E Eldridge Powers*(74) Attorney, Agent, or Firm* — Absolute Technology Law Group, LLC**(57) CLAIM**

The ornamental design for a hat with dry erase surface, as shown and described.

DESCRIPTION

FIG. 1 is a perspective view of a hat with dry erase surface showing my new design;

FIG. 2 is a front view thereof;

FIG. 3 is a left side view thereof, the right side being a mirror image;

FIG. 4 is a rear view thereof; and,

FIG. 5 is a top view thereof.

The broken lines shown in the drawings represent stitching and form no part of the claimed design.
